US00D409151S

United States Patent [19]

Berger et al.

[11] Patent Number: Des. 409,151

[45] Date of Patent: ** May 4, 1999

[54] ELASTOMERIC SWITCH

[75] Inventors: **John W. Berger**, Laguna Niguel; **Ted L. Nichols**, Mission Viejo; **Andry Kertatama**, Montebello; **James F. Gust**, Temecula, all of Calif.

[73] Assignee: **Staco Switch, Inc.**, Costa Mesa, Calif.

[**] Term: 14 Years

[21] Appl. No.: 29/078,343

[22] Filed: Oct. 21, 1997

[57] CLAIM

We claim the ornamental design for an elastomeric switch, as shown and described.

DESCRIPTION

FIG. 1 shows a top perspective view of our new design for an elastomeric switch.

FIG. 2 is a perspective view of the switch looking from the under side thereof, opposite from that shown in FIG. 1.

FIG. 3 is a front elevation view thereof, the rear, right and left sides being identical thereto.

FIG. 4 shows a top plan view of the switch; and, FIG. 5 shows a bottom view looking upwardly at the switch.
